DISC CARTRIDGE FOR DATA PROCESSING EQUIPMENT

Robert F. Heidecker, Longmont, Albin Kenneth Johnson, Arvada, Glenn W. Monigle, Denver, and Galen B. Royer, Boulder, Colo., assignors to Dynastor, Inc., Denver, Colo.

Filed Oct. 29, 1974, Ser. No. 518,279

Term of patent 14 years

Int. Cl. D14—02

U.S. Cl. D26—5 C

FIG. 2

FIG. 1

FIG. 3

FIG. 5

FIG. 4

FIG. 1 is a top plan view of a disc cartridge for data processing equipment showing our new design.

FIG. 2 is a front view thereof.

FIG. 3 is a rear elevational view thereof.

FIG. 4 is a bottom plan view thereof.

FIG. 5 is a side view thereof.

We claim:

The ornamental design for a disc cartridge for data processing equipment, substantially as shown and described.
